UNITED STATES PATENT OFFICE.

JAMES L. BUTLER, OF AKRON, AND NORMAN SLEE, OF BARBERTON, OHIO, ASSIGNEES
TO THE BABCOCK & WILCOX COMPANY, OF NEW YORK, N. Y., A CORPORATION OF
NEW JERSEY.

WATER-TUBE BOILER.

981,377.

Specification of Letters Patent. Patented Jan. 10, 1911.

Application filed April 8, 1907. Serial No. 366,897.

To all whom it may concern:

Be it known that we, JAMES L. BUTLER, of Akron, Summit county, Ohio, and NORMAN SLEE, of Barberton, Summit county, 5 Ohio, have invented a new and useful Improvement in Water-Tube Boilers, of which the following is a full, clear, and exact description, reference being had to the accompanying drawings, forming part of this 10 specification, in which:—

Figure 1 is a longitudinal vertical section of a boiler constructed in accordance with our invention; and Fig. 2 is a front elevation of the same one-half in vertical cross- 15 section.

Our invention relates to providing a wa- 20 ter tube boiler suitable for locations where considerable power is demanded with very limited head room.

20 In the drawings, 2 represents a transverse steam and water drum, and 3 a mud drum located somewhat below the steam and water drum and a considerable distance to the rear thereof. These two drums are connect- 25 ed by sets of tubes, of which we have shown three, namely, 4, 5 and 6, these sets being separated by baffles 7 and 8. The furnace 9 is in front of the tubes and drums and below the level of the drum 2, being of the usual 30 external type as used on Stirling boilers. In addition to the bridge wall 10 at the rear of the furnace, we preferably employ a rear bridge wall 11 in front of the mud drum 3, which protects the mud drum and prevents 35 leakage of gases directly to the stack opening 12. The front part of the boiler is prefer- 40 ably supported upon uprights or columns 13, which may be embedded in the side walls 14, as shown in Fig. 2. In this figure, 15 is the fire brick or refractory lining of the wall setting.

In the use of the boiler, water is prefer- 45 ably fed into the rear drum and there will be a circulation forwardly and upwardly through the tubes 4, and a circular circula- 50 tion rearwardly and downwardly through the tubes 6. There is probably an up and down circulation among the tubes 5, being up through some of the tubes and down through others. The flame and products of 55 combustion pass rearwardly in a horizontal direction among the horizontally extending tubes 4 to the rear end of the baffle 7; thence flow forwardly among the tubes 5 until they reach the forward end of the baffle 8, and

thence pass rearwardly among the tubes 6 to the outlet flue 12.

The advantages of our invention result from the large capacity or horse power which is obtained with very low head room. 60 By using the two drums and the horizontally extending curved tubes arranged in sets, and entering said drums, we can obtain a good circulation and economy, while at the same time the boiler may be placed in situations which could not receive boilers of ordinary types. 65

Many changes may be made in the form and arrangement of the drums, tubes, fur- 70 nace, &c., without departing from our in- vention.

We claim:—

1. A water tube boiler comprising a front transverse steam and water drum and a rear transverse mud drum connected thereto by sets of horizontally extending tubes having reversely curved end portions, a combustion chamber in front of the steam and water drum, and two horizontally extending baffles extending between the tubes in oppo- 75 site directions from the two drums and over- 80 lapping each other, dividing the tubes into three sets and giving the gases three horizontal passes among the tubes, substantially as described. 85

2. A water tube boiler comprising a front transverse steam and water drum and a rear transverse mud drum connected thereto by three sets of horizontally extending tubes having reversely curved end portions, a fur- 90 nace in front of the steam and water drum, a lower horizontal baffle extending rear- 95 wardly from the steam and water drum and across the top of the lower set of tubes, an upper horizontal baffle extending forwardly from the mud drum between the middle and upper sets of tubes and overlapping the lower baffle, a roof over the upper tubes, and a rear wall having an off-take flue at the rear of the upper tubes, substantially as de- 100 scribed.

3. A water tube boiler comprising a front transverse steam and water drum, a rear transverse mud drum at a slightly lower level, three sets of horizontally extending tubes 105 having reversely curved ends connecting the drums and each having a plurality of rows, a furnace arranged in front of the steam and water drum and opening into the space oc- cupied by the forward curved ends of the 110

lower set of tubes, a baffle extending from the front drum rearwardly between the first or lower set and the next set of tubes, another baffle extending from the mud drum 5 forwardly between the second or middle and the upper set of tubes and overlapping the lower baffle, and a deflector bridge wall in front of the mud drum to protect and prevent short-circuiting of gases, the rear wall 10 having an off-take port in the rear of the upper set of tubes, all the water tubes connecting the two said drums, substantially as described.

4. A water tube boiler comprising a setting, a transverse mud drum at the bottom 15 and back of the setting, a transverse steam and water drum at the front and top of the setting, at least three sets of substantially

horizontal tubes connecting the drums, a furnace in front of the setting and communicating with the space below the tubes, and 20 baffles disposed to provide a rearward pass containing the lower set of tubes, a forward pass containing the intermediate set of tubes, and a rearward and downward pass containing 25 the upper set of tubes, and an outlet at the rear of the downwardly extending portion of the upper pass, substantially as described.

In testimony whereof, we have hereunto 30 set our hands.

JAMES L. BUTLER.
NORMAN SLEE.
